US0D1014496S

(12) **United States Design Patent** (10) **Patent No.:** **US D1,014,496 S**
(45) **Date of Patent:** **** Feb. 13, 2024**

(54) **DATA TRANSMISSION DEVICE**

(71) Applicant: **SumUp Services GmbH**, Berlin (DE)

(72) Inventors: **Tomer Sabag**, Berlin (DE); **Ricardo Maffazioli**, Berlin (DE)

(73) Assignee: **SUMUP PAYMENTS LTD.**, London (GB)

(**) Term: **15 Years**

(21) Appl. No.: **29/769,477**

(22) Filed: **Feb. 5, 2021**

(30) **Foreign Application Priority Data**

Aug. 7, 2020 (EM) 008087811-0001

(57) **CLAIM**

The ornamental design for a data transmission device, as shown and described.

DESCRIPTION

FIG. 1 is a front, top, right perspective view of a data transmission device;

FIG. 2 is a right side elevation view thereof;

FIG. 3 is a left side elevation view thereof;

FIG. 4 is a front plan view thereof;

FIG. 5 is a rear plan view thereof;

FIG. 6 is a top elevation view thereof; and,

FIG. 7 is a bottom elevation view thereof.

The broken line in the drawings depicts a portion of the data transmission device that forms no part of the claimed design.

1 Claim, 7 Drawing Sheets
